United States Patent Office

Des. 183,220

Patented July 15, 1958

183,220

UTENSIL HANDLE

Arthur A. March, Bridgeport, Conn., assignor to Table Appointments, Inc., New York, N. Y., a corporation of New York

Application June 18, 1957, Serial No. 46,689

Term of patent 14 years

(Cl. D44—29)

Fig. 1

Fig. 2

Fig. 3

Fig. 4

Fig. 5

Fig. 2 is a top plan view of the utensil handle shown in Fig. 1;

Fig. 3 is a bottom view of the utensil handle shown in Fig. 1;

Fig. 4 is a left end view of the utensil handle shown in Fig. 1; and

Fig. 5 is a right end view thereof.

I claim:

The ornamental design for a utensil handle, as shown.
